(57) **CLAIM**

(21) Appl. No.: **29/289,116**

The ornamental design for a apparatus for measuring electrical parameters, as shown and described.

(22) Filed: **Jul. 6, 2007**

(30) **Foreign Application Priority Data**

DESCRIPTION

Jan. 19, 2007 (CH) 133588

FIG. 1 is a top perspective view of the measuring apparatus; FIG. 2 is a lower perspective view of the apparatus of FIG. 1; FIG. 3 is a top plan view of the apparatus of FIGS. 1 and 2; FIG. 4 is an end view of the apparatus as depicted in FIG. 3; FIG. 5 is a left plan view of the apparatus shown in FIG. 3; FIG. 6 is a right plan view of the apparatus shown in FIG. 3; FIG. 7 is an end view of the apparatus shown in FIG. 3; and, FIG. 8 is a lower plan view of the device shown in FIG. 2.
